(57) **CLAIM**

The ornamental design for a sports bag as shown and described.

DESCRIPTION

FIG. 1 is a perspective view of a sports bag, in an open configuration, showing the new design;

FIG. 2 is a perspective view of the sports bag, in a closed configuration, showing the new design;

FIG. 3 is a front elevation view thereof;

FIG. 4 is a rear elevation view thereof;

FIG. 5 is a left side elevation view thereof;

FIG. 6 is a right side elevation view thereof; and,

FIG. 7 is a top plan view thereof.

The broken lines on the sports bag depict stitching and are part of the claimed design.

1 Claim, 5 Drawing Sheets
